ELLIOTT CLEMENCE, OF NEW YORK, N. Y., ASSIGNOR, BY MESNE ASSIGNMENTS, TO THE MONOWATT ELECTRIC CORPORATION, OF BRIDGEPORT, CONNECTICUT, A CORPORATION OF CONNECTICUT

LAMP-SOCKET-PLUG TAP

Application filed November 15, 1927. Serial No. 233,438.

The present invention relates to lamp socket plug taps and is more particularly directed toward a plural lamp socket having provisions for connecting in four electrical devices 5 such as two lamps or other threaded connectors and two attachment plug caps or other forms of pronged connectors.

The present invention contemplates a device of this nature which consists essentially of 10 a casing made out of two like halves of molded insulating material and within which is housed the contacts for the various outlets.

According to the present invention, all of 15 the metal parts except the external male screw shell (where it is employed) may be inserted into one of the casing halves and held thereby in position without the employment of solder, whereupon the other casing half may be placed in position and the two parts secured 20 together by a bolt passing through the casing. Where the current supply portion of the electrical connector is in the form of a screw shell, this screw shell is adapted to be placed in position after the casing parts and in- 25 closed elements have been secured together. It connects with the inclosed conductors to supply one half of the circuit and is preferably permanently secured in position on the casing.

30 While the structure herein disclosed is called a four-way tap, it is, in actuality a five way tap, as provision for five separate connections are involved herein.

One outstanding advantage accomplished 35 by my present structure relates to ease and readiness of assembly of the tap owing to the few and simple parts involved.

Another advantage relates to ease of locking the component units into a complete as- 40 sembly.

Another advantage relates to the manner of amplifying the internally mounted metallic circuit forming members, by the addition of 45 a few simple, additional metallic parts, with proper positioning spaces in the outer insulator body, the capacity of such taps is doubled in capacity, thereby permitting the connecting of and distribution of electric current from a single socket to four separate circuits, 50 simultaneously.

In the present embodiment a single, preferably threaded, tap or plug connection permits of attaching my device to a socket, and in turn is provided with a pair of threaded sockets, whereby two other threaded circuit connections may be made, and intermediate of these latter sockets but adjacent thereto, is oppositely located a pair of plug in connections for cooperation with the blade contacts 55 of attachment plugs, taps, and the like. 60

These and other capabilities will be ascertained as the herein description proceeds, and it is obvious that modifications may be made in the structure herein without departing 65 from the spirit of this invention or the scope of the appended claims.

In the drawings Fig. 1 is a side view of my device, assembled; Fig. 2 is an open view thereof with one of the enclosing insulator members removed; Fig. 3 is an open view of 70 one of the insulator halves; Fig. 4 is a fragmentary side view of the upper or light socket connection end of either of the insulator halves; Fig. 5 is a combined view of the side 75 and end views of the major metallic circuit conducting elements; Fig. 6 is a triple view, showing the plan, side and end views of the minor metallic circuit conductor; Fig. 7 is a side view, reduced, of my device, showing the same in position to receive two simultaneous 80 prong taps; Fig. 8 is a side view of one of the internally mounted threaded socket shells; and Fig. 9 is a view of the same, rotated at about 90 degrees.

In Fig. 1 the electrical connector is shown 85 as comprising a main threaded contact ferrule 1, which may be screwed into any screw socket for direct connection to a source of electric current. Branching from the ferrule 1 are a pair of divergent threaded sockets 2 and 3 for receiving therein lamps or other threaded connectors for a continuation of these two 90 separate circuits as desired. Centrally of these latter divergent sockets 2 and 3 are located, upon opposite sides of my complete device, one each of a pair of plug taps 4 and 5, see also Fig. 7, into which may be plugged also for simultaneous use, if desired, a pair of pronged plug-in taps 6 and 7, whereby two 95 other circuits may be connected thereto. 100

Thus it will be noted, that, plus a main socket connection, I have provided four additional circuit connections, for distribution of current to as many separate circuits singly or together.

The insulator housing 8 comprises a pair of duplicate parts, identical in structure, and seatings, having a single unkeyed meeting as indicated by the line 9, Fig. 7, whereby they 10 match together to form a complete enclosure, but these halves are connected at these planes, against moving, by the keying action of the various contained circuit forming elements, which rest, purposely, half of their structures 15 in each half of the insulator housing 8. By this arrangement, the mating halves of the housing may be assembled upon their contained circuit forming conductors and be held in firm assembly by a single centrally located locking screw and nut, generally noted by 10, Figs. 1 and 2, through bore 11, Fig. 3, suitable countersunk seats being provided at the exterior of these bores to permit of keeping 20 the head of the screw 10 and its nut below 25 the outer surface of the exterior of the housing 8.

The duplicate halves of the housing 8 are provided at their sockets 2 and 3 near the bottom thereof with an annular groove 12, which 30 in assembly receives the flared flange 13 of the threaded metallic socket shell 14, which in turn has an upwardly, outwardly upstanding connector 15 thereon, Figs. 8 and 9, which fits into the grooves or seats 16 and 17 shown 35 in Fig. 3 of each of the sockets 2 and 3, and is sufficient in length to extend outside of said grooves as shown in Fig. 2, thereby to make electrical contact with the threaded metallic ferrule or male screw shell 1, at its interior, 40 the said ferrule 1 being fitted thereover and about the main socket connector neck extension 19 of the assembled housing 8. Thus, through the above, a completed leg of the socket circuits is formed.

The ferrule 1 is of thin sheet metal formation and has rolled threads as shown, and is fitted over the smooth cylindrical tip or neck generally denoted by 19, formed by the junction of the two duplicate parts of the housing 50 8. The ferrule 1 is locked to the said neck 19, on both housing parts, by pressing the lower edge thereof into molded seat depressions 20, Fig. 4, thereby forming locking indentations 21, Fig. 1.

The parts of housing 8 are, further, provided with a continuous Y shaped channel or seat generally denoted by 22, 23, 24 and 25, which runs from the top 19 down the center thereof, and dividing near the center there- 60 of as at 24, 25, and terminate at the divergent chambers of the sockets 2 and 3. In this continuous channel or seat is located a flat, con- formed, metallic conductor generally de- noted by 26, Figs. 2, and 5, and as shown in 65 the latter figure comprises a single piece of

flat metal, having two downstanding arms 27, 28 bent from an upper angle-shaped contact junction 29, which in assembly, Figs. 1 and 2, resiliently projects above the upper end of the neck 19, for making the inner contact with a stock screw socket normally installed in the source of electric supply. The housing 8 at this point is provided with a flaring wedge like seat 32 in which the lower angled portions 30 and 31 of the contact 29 are seated to resist inward thrust and displacement.

The contact 26, further, has divergent extensions 33, 34 extending from the arms 27-28, Fig. 5, and these in turn have two extensions 35-36 respectively, which are bent inwardly, and as indicated in the sprung, seated position in Fig. 2, these latter extensions form the center contacts for the sockets 2 and 3.

Upon this socket circuit forming contact 26, is also affixed one leg of the prong-lug forming circuits, and this comprises a resilient, two tongued contact member having an arm 37 which is riveted to the leg 27 of contact 26, and is provided at its lower end with a pair of opposed, bent, spring contacts 38 and 39. These latter contacts when in assembled position in the housing 8, are received in seat 40, Figs. 2 and 3, and blade contact openings or prong plug bores 41 Figs. 1, 2, and 3, which extend entirely through to the exterior of the housing 8 and form with said contacts 38 and 39, one leg of the circuit for the prong plugs 6 and 7, Fig. 7.

The other leg of the prong plug circuit is formed by a separate, simple spring contact as shown in the three views Fig. 6, and comprises a somewhat cruciform structure formed of a two tongued contact 42-43, the base of which 44, is riveted centrally of a single cross-contact member 45, at right angles thereto, the outer ends of the contact 45 being slightly bent, so as to resiliently engage the outer surface of the opposed threaded socket members 14, shown in Fig. 2, when this cruciform contact 44-45 is introduced into seat 46 and prong-plug bore 47, which like rectangular bore 41 passes to the exterior of the housing 8, and forms the other leg of the circuit to that described for parts 38-39.

Thus the socket circuits (2 and 3) are closed as follows, from ferrule, through arm 15 of the socket screw shells 14, to any screwed in connector (not shown) thence across to bent extensions 35-36 to spring contact 29, thus completing the two socket circuits.

For the both opposing prong circuits, the current flows as follows, from the ferrule 1, to arms 15 of the socket ferrules 14, thence through the arms 45 of the cruciform contact to its spring contacts 42-43, thence across plugs 6 and 7, Fig. 7, to spring contacts

38—39, thence to arm 37 to central upper contact 29.

In order to take up the torsional strain of screwing in and out of lamps or threaded plugs in the sockets 2 and 3, I have provided a dual key arrangement in the housing 8, such provision being the cutting of a pair of notches 48—48 upon the opposite sides of the threaded screw shells 14, as at Fig. 8, and forming of corresponding upstanding key abutments 47—47' in each part of the housing as at Figs. 2 and 3. The interengagement of these parts prevents the contact arm 15 on the screw shells 14 being misaligned in assembly or twisted out of position in use. Thus it will be observed that four circuits may be simultaneously connected into my improved socket, or a single circuit may be plugged, in, at will, without possibility of short circuit, and in a compact plug of few parts.

In assembling the multiple lamp socket, the contact assemblies illustrated in Figure 5 are inserted in place with the divergent extensions 33 and 34 in the passageway interconnecting the upper ends of the socket openings and so that the spring tips 35 and 36 are in place to contact with the center contact of the lamp or the like. One of the spring contacts 38 or 39 passes down into one of the blade receiving holes 41 and the body portion 27 of the connector extends up through the passageways 22 and 23 and out through the opening in the tip of the housing part. The contact assembly shown in Figure 6 is placed with the strip 45 in the cross channel 46 with one of the blade contacts 42 or 43 housed in the laterally extending opening 47. The screw shells 14 are placed in position with the flanges 13 thereof resting in the grooves 12, the notches 48 engaging the lugs 47' and with the strip extensions 15 extending out from the channels 16 and 17. The other housing part may then be placed in position on the projecting conductors and the bolt 10 secures the housing parts and inclosed conductors together as a unit. The male screw ferrule 1 may then be passed down onto the tip of the casing and pressed into the recesses 20 to secure it in place.

It is obvious that the invention may be embodied in many forms and constructions, and I wish it to be understood that the particular form shown is but one of the many forms. Various modifications and changes being possible, I do not limit myself in any way with respect thereto.

Having thus described my invention what I claim is:

1. In a socket of the class described, a conductor comprising a pair of resiliently connected arms bent from an upper angle-shaped contact junction, and having two divergent contact extensions inwardly turned at their extremities, and a third contact inter-

mediate of said divergent contacts carrying a pair of opposed resilient prong engaging contacts thereon.

2. In a socket of the class described, a conductor comprising a pair of resiliently connected arms bent from an upper angle-shaped contact junction, and having two divergent contact extensions inwardly turned at their extremities, and a third contact extending intermediate of said divergent contacts carrying a pair of opposed resilient prong engaging contacts thereon at right angles to said divergent contact arms. 75

3. In a socket of the class described, a conductor comprising a pair of resiliently connected arms bent from an upper angle-shaped contact junction, and having two divergent contact extensions inwardly turned, at their extremities, a third contact riveted intermediate of said divergent contacts, upon one arm thereof, and an opposed resilient prong engaging contact riveted thereon, located at right angles to said divergent contact arms. 80

4. In a plural lamp socket, an insulating casing composed of two casing halves of molded insulating material secured together, said casing having a male socket shell receiving upper tip and a pair of downwardly divergent socket shell receiving openings each provided with bottom forming end walls and a pair of laterally extending openings for blade contacts, there being a cross channel extending from the bottom of one socket opening to the bottom of the other socket opening and communicating with the two laterally extending openings for blade contacts, said cross channel also communicating with a passageway extending out through the center of the tip, and a preassembled contact unit for one side of the circuit, said unit having two center contacts for the sockets, two spring contacts for the blade contact openings and a supply lead extending out through the tip center, and being insertible into one of the casing halves before the other half is placed in position. 95

5. In a plural lamp socket, an insulating casing composed of two casing halves of molded insulating material secured together, said casing having a pair of divergent socket receiving openings whose adjacent sides are interconnected by a cross channel which communicates with two laterally extending openings for blade contacts, a pair of socket shells in the socket openings, and a contact member disposed in the channel and engaging the outside of the shells, the contact member having spring blade contacts in the blade contact openings. 115

6. In a plural lamp socket, an insulating casing composed of two casing halves of molded insulating material secured together, said casing having a male socket shell receiving upper tip and a pair of down- 120

- wardly divergent socket shell receiving openings whose adjacent sides are interconnected by a cross channel which communicates with two laterally extending openings for blade contacts, each socket opening being provided with a bottom forming end wall having a passageway extending from the outer portion of the socket opening through the bottom wall and to the outside of the casing adjacent the tip, a pair of socket shells in the socket openings, a contact member disposed in the cross channel and engaging the outside of the shells, the contact member having spring blade contacts in the blade contact openings, and a male screw shell on the tip, the socket shells having strips extending through said passageways to connect the socket shells to the male shell.
7. In a plural lamp socket, an insulating casing composed of two casing halves of molded insulating material secured together, said casing having a male socket shell receiving upper tip and a pair of downwardly divergent socket shell receiving openings each provided with bottom forming end walls and a pair of laterally extending openings for blade contacts, there being a cross channel extending from the bottom of one socket opening to the bottom of the other socket opening and communicating with the two laterally extending openings for blade contacts, said cross channel also communicating with a passageway extending out through the center of the tip, a cross channel interconnecting the adjacent sides of the socket receiving openings and communicating with two laterally extending openings for blade contacts disposed parallel to the first mentioned openings for blade contacts, and passageways extending from the outer portions of the socket openings through the bottom walls of the sockets and to the outside of the casing adjacent the tip, a pair of socket shells in the socket openings, the shells having strips extending out through the last mentioned passageways, a contact member disposed in the cross channel and engaging the outside of the shells, said contact member having spring contacts in the last mentioned blade contact openings, a preassembled contact unit having two center contacts for the sockets, two spring contacts for the first mentioned contact openings and a supply lead extending out through the tip center, all said conducting parts being insertible into one of the casing halves before the other half is placed in position, and a male screw shell surrounding the tip and contacting with the strips extending from the socket shells.
60. Signed at New York, in the county of New York and State of New York, this 11th day of November, A. D. 1927.

ELLIOTT CLEMENCE.
